UNITED STATES PATENT OFFICE.

ARTHUR ROOT, OF WILKES-BARRE, PENNSYLVANIA.

BRICK-MACHINE.

1,377,525.

Patented May 10, 1921.

Application filed June 9, 1917. Serial No. 173,756.

To all whom it may concern:

Be it known that I, ARTHUR ROOT, a citizen of the United States, residing at Wilkes-Barre, in the county of Luzerne, State of 5 Pennsylvania, have invented a new and useful Brick-Machine, of which the following is a specification.

My invention relates to improvements in brick machines. The object is to provide improved means for cutting a continuously 10 moving clay bar into bricks.

The invention comprises improved means for supporting, reciprocating and rotating at required intervals, the cutting wire reel, 15 including automatic means for shifting the wire reel, its housing and supporting means, and for simultaneously throwing into and out of action the clutch device for rotating the reel.

20 The invention comprises improved means for varying or adjusting the friction clutch connection between the measuring pulley and the driving shaft for rotating the cutting reel; safety means included in such actuation, improved oiling devices and other details of construction.

Referring to the drawings, which illustrate merely by way of example a suitable embodiment of my invention—

30 Fig. 1 is a side elevation.

Fig. 2 is a plan view.

Fig. 3 is a vertical section on line 3, 3 of Fig. 2.

Fig. 4 is a vertical section on line 4, 4 of 35 Fig. 1 with the clutch in.

Fig. 5 is a section on line 5, 5 of Fig. 2.

Fig. 6 is a detail on an enlarged scale of the clutch shifting mechanism.

Fig. 7 is a similar view with parts in different position.

Fig. 8 is a sectional view on an enlarged scale of the positive clutch mechanism.

Fig. 9 is a cross section on line 9, 9 of Fig. 8.

45 Fig. 10 is a plan view on an enlarged scale of the oiling device for the platen.

Fig. 11 is a section on line 11, 11 of Fig. 10.

Fig. 12 is a side elevation on an enlarged scale of cam 60 and associated mechanism.

50 Fig. 13 is a plan view of same.

Fig. 14 is a detail view in perspective of the lever 65 and its associated mechanism.

Fig. 15 is a section on line 15, 15 of Fig. 3.

Similar numerals refer to similar parts throughout the several views.

The wire reel comprises the two gear wheels 14 supported and rotating on the flanges 15 of the stationary housing 16. These gear wheels are connected by the three cross bars 17 which carry the wire hooks 18 of the usual construction. To these hooks 18 are secured one of the ends of each of the wires 19, the other ends being secured to the rings 20 rotatably mounted on the shaft or beam 21 between the spacing shoulders 22. 60 The beam 21 is secured at each end to the housing frame 16. This beam also carries the platen or series of platens 23 which support the clay bar as the wires pass through the same.

70 *Movably mounted housing.*—The housing 16 is provided with the pair of extensions or wings 24 on one side thereof and the pair of extensions or wings 25 on the other side. These wings engage on the top of the rollers 26 and 27 mounted on the stationary framework. Rollers 26 are mounted on the housings 28 of the pinions 29, while rollers 27 are mounted on the framework at the other side of housing 16. These rollers are provided with peripheral channels to receive the co-operating channel formation on the wings to prevent lateral play. This roller support of the housing 16 permits of a horizontal reciprocating movement of the said housing.

80 *Reciprocation of wire reel.*—This reciprocating movement of housing 16 is caused by a pair of oppositely acting cams 30 and 31 secured to and rotating with the regulating shaft 32 of the regulating or measuring pulley 33. The purpose of this movement is to cause the wire reel to move longitudinally or horizontally with the clay bar while the reel rotates during the cutting operation through the bar. After the cutting action the rotation of the reel is arrested and the reel is moved back horizontally to initial position for receiving and operating upon another portion of the advancing clay bar.

90 *Rotation of the wire reel.*—The following 100

mechanism is provided for causing the periodic or intermittent rotative movement of the wire reel. The shaft 34 is provided with the driving pulley 35 driven from any suitable source of power.

On shaft 34 is mounted the hollow shaft 36 carrying the pinions 29 and 29'. This shaft 36 is supported in the bearings 37. Another hollow shaft 38 is mounted on shaft 10 34 and supported in the bearing 39. On hollow shaft 38 is secured the pinion 40 coöperating with bevel gear 54 on regulating shaft 32 carrying measuring pulley 33. A friction element 41 is secured on shaft 38 and co-15 operates with friction element 42 feathered on the driving shaft 34. A hand wheel 43 mounted on shaft 34, is provided with a threaded extension 44 operating in the threaded housing 39, and serves to adjust the 20 efficiency of frictional engagement between said friction elements. The object of this adjustment is to secure the required transmission of power from the driving shaft 34 through the friction elements 41 and 25 42, to the measuring pulley, depending upon the speed of travel and the consistency of the clay bar.

Pinion 29 is feathered on shaft 36 and is provided with the extension having collars 30 46, between which is loosely mounted the sleeve 45. This sleeve 45 is provided with trunnions 47 which engage the bifurcated end of lever 48. This lever 48 is mounted on shaft 49 having fixed bearings. To 35 shaft 49 is secured the lever 50 having at its free end the roller 51. To shaft 49 is also secured the lever 52 having at its free end the roller 53.

Mounted on the regulating shaft 32 of the 40 regulating or measuring pulley 33 is the cam 56 adapted to engage roller 51 on lever 50. Secured on shaft 57 is the bevel gear 58 which coöperates with gear 59 secured to hollow shaft 36. Mounted on 45 shaft 57 is the cam 60 adapted to engage roller 53 and actuate lever 52. It will be understood that the actuation of these levers 50 and 52 serves to rock lever 48 in opposite directions respectively and thus, 50 through sleeve 45 and collars 46, to shift the pinion 29 to the right or to the left.

Mounted on one end of pinion 29, see 55 Figs. 8 and 9, is the formation 61 having its outer portion 61' of smooth circular formation, while the portion adjacent the pinion is of ratchet formation, that is provided with the ratchet projections 61². These in the example illustrated are four in number and evenly spaced. These projections are 60 provided with the beveled edges 61³ extending down to the smooth circular portion 61'.

Mounted on the shaft 34 is the cylindrical housing 63 provided with the pawls 64 projecting through the wall of housing 63

and engaging the formation 61. These 65 pawls are controlled by the springs 62. The lower end of each pawl is provided with a bevel face for coöperation with the beveled edges 61³ of the ratchet formation.

When the pawls 64 engage the smooth 70 portion 61' of the formation 61, independent rotative movement is permitted between housing 63 and formation 61. When the formation 61 is shifted to the left the pawls engage the ratchet formation thereby forming 75 a positive clutch as shown in Fig. 8.

When this shifting movement of formation 61 into the housing 63, takes place, with the projections 61² in direct line with the pawls, the beveled formations permit 80 the pawls to ride up to the top of the projections, and upon further relative rotation between the parts the pawls descend into the recesses between the ratchet teeth or projections and thus form the positive clutch 85 as stated. It will thus be seen that the lateral shifting of the formation 61 into the housing 63 is always permitted notwithstanding the relative positions of the pawls and ratchet teeth. Each pawl engages a 90 corresponding ratchet tooth simultaneously, thus evenly dividing the stress between the rotating parts.

This movement of pinion 29 and formation 61 to the left is caused by the engagement of cam 56 with roller 51 on lever 50. It follows from this arrangement, that when said pawls and projections are in engagement, the rotative movement of shaft 34 is communicated to shaft 36 and pinions 95 29 and 29'. This causes a corresponding rotative movement of the wire reel. After a predetermined rotative movement of pinions 29, 29' and the wire reel, the shaft 57 carrying cam 60 is correspondingly rotated 100 through the gears 58 and 59, causing the cam 60 to engage the roller 53 to actuate the lever 52 to rock lever 48 to the right, thus moving the ratchet or clutch member 61 out of engagement with the pawls 64, 110 which results in the interruption of the rotative movement of the reel until a further rotative movement of cam 56 causes the actuation through levers 50 and 48 of pinion 29 to the left to bring the pawl and ratchet 115 clutch mechanism again into operative relationship when the cutting operation is repeated.

On shaft 49 is also secured the lever 65 provided at each end with the hook or stop 120 66. This lever is so secured to shaft 49 that its axis of movement corresponding to the axis of the shaft is at the middle part of the lever but so that the lever presents a clear track for the roller 67 to travel from one end to the other, or from one side to the other of its axis of movement, as clearly shown in Fig. 14. Roller 67 is connected to one end of

spring 68, the other end being adjustably connected to a stationary part 69. The purpose of this over-the-center movement of the spring controlled roller is to snap the shaft 49 to its extreme limit of movement in either direction, after sufficient preliminary movement has been communicated thereto by cam 56 or cam 60. The further function of this mechanism is to hold said parts in said extreme position until again actuated.

A preferred construction of lever 52 is shown in Figs. 6 and 7 in which arm 70 is rigidly secured to shaft 49. Lever 52 is pivoted at 71 to the outer end of arm 70. The underside of the end of lever 52 next to shaft 49 is cut away or rounded as shown so that lever 52 may be rotated on pivot 71 in the clockwise direction. The upper portion of the end of lever 52 normally engages shaft 49 and so limits its counter-clockwise movement. The spring 72, in tension between arm 73, which is rigid with shaft 49, and the outer end of lever 52, normally holds the lever in the position shown. The object of this construction is to provide a safety means, whereby levers 50 and 52 may have independent movement, in case, for any reason, one becomes locked against movement when the other is actuated.

Cam 60, see Figs. 12 and 13, is loosely mounted on the shaft 57 and is provided with a sector shaped recess for receiving the pin 87 which is fixed on shaft 57. The spiral spring 85 connected between the shaft 35 and the cam normally maintains the cam in position with one margin of the sector shaped recess in engagement with the pin 87. In operation, when the cam 60 engages the roller 53 of lever 70 as shown in Fig. 7, the shaft 57 is permitted to have a quarter turn before further actuating the cam 60 to depress the lever 70. This results in a dwell corresponding to the time required for a quarter turn of the shaft and for the pin 87 to move from one side of the sector shaped recess to the other, whereupon the cam 60 is further rotated to depress the lever 70 sufficiently for it to be carried to its lowest position by the operation of the spring actuated lever 65, whereupon the cam 60 being released from the roller 53 is carried a quarter turn forward by the action of the spring 85 which was compressed or put under tension by the quarter turn of the shaft, while the cam was being held in the position shown in Fig. 7. By this construction the necessary dwell is secured before the actuation of the lever 70 to permit the completion of the cutting movement of the reel, and the quarter turn spring actuated movement of the cam after depressing the lever 70 carries the cam free of the roller 53 so that the lever 70 may be actuated in the opposite direction without interfering with the cam 60 when lever 50 is depressed.

Oiling means.—In order to facilitate the passage of the clay bar over the platens it is desirable to supply a lubricant to the faces of the bar that are to contact with the platens, that is, the underside and rear face. For this purpose I provide the oil reservoir 75 with suitable piping 76 leading to the roller 77 having a vertical axis, and piping 78 leading to the receptacle 79 in which is placed the roller 80. These rollers are preferably provided with a surface of oil conveying substances, and are adapted to engage the bottom and rear surface of the clay bar as it passes from the measuring pulley to the platens. A yielding pressure engagement is maintained between roller 77 and the surface of the clay bar by the action of spring 88, engaging the pivoted lever 89 which supports the upper end of the roller axis.

The receptacle 79 containing the roller 80 is provided with an apertured covering plate 81 having its top surface in the plane of the horizontal surfaces of the platens. The aperture 82 of the plate 81 is adapted to permit the roller 80 to project slightly through the same and above the surface of the platen. The front margin of this aperture is beveled on the underside thus forming a sharp or wedge-shaped edge 81' adapted to engage the periphery of the roller to divert or scrape a portion of the oil therefrom, thus serving most efficiently to feed oil to the underside of the clay bar to be carried forwardly over the platens.

This plate 81 is provided with marginal recesses 83 for engaging lugs or projections 84 on the receptacle to prevent horizontal displacement, but to permit arbitrary removal of the plate from the receptacle when it is desired to have access thereto.

In operation, the clay bar is delivered over the measuring pulley 33, and the oiling roller 79 to the platens 23. When a sufficient length of clay bar has moved along the platens, the cam 56 on measuring pulley shaft 32 causes a shifting of one of the gears 29 to render effective the positive clutch mechanism including elements 61 and 64 as above described. This causes a rotative movement of the wire reel to bring a set of cutting wires 19 through the clay bar. At the same time the wire reel and its housing and the platens are moved forwardly with the clay bar by means of the cam 31 on the shaft of the measuring pulley, acting upon the roller 31' connected with said housing. This assures a straight cut of the wires through the clay bar, that is at right angles with its longitudinal extension. At the end of the third of a turn movement of the reel the cam 60 actuates lever 50 to shift one of the pinions 29 with its clutch element out of engagement with the co-operating clutch elements, whereupon the rotative movement of the reel is arrested. At the same time the

cam 30 operates upon roller 30', which is connected with the housing, to cause a return movement of housing, and reel and platens to initial position. The cam 31 is so shaped and arranged as to cause a slow forward movement of the reel exactly timed with the movement of the clay bar. The cam 30 is so shaped as to cause a comparatively quick return movement of the reel after the cutting operation and after the reel has ceased to rotate.

The cam 56, mounted on the measuring wheel shaft, is timed to throw the clutch elements 61 and 64 into operative relationship 15 to start the rotation of the cutting reel as soon as the clay bar has moved to extend across the several platens 23. The cam 60 is timed to actuate lever 50, 52 to throw said clutch elements out of operative relationship 20 as soon as the cutting wires have passed through the bar. This lever 50, 52 is compound and spring controlled as to its elements for purposes of safety as already described. The cam 60 is mounted on its actuating shaft with a spring controlled lost motion connection for the purposes already 25 described.

The friction element 41 is secured to and rotates with the hollow shaft 38. This shaft 30 is directly geared through 40 and 54 with the regulating shaft 32 and is therefore subject to the control of the clay bar. This shaft 38 also carries the driving elements of clutch 61, 64. The friction clutch element 35 42 is feathered on the main power shaft 34 and cooperates with the friction clutch element 41. The efficiency of frictional engagement is controlled or adjusted by hand wheel 43 as already described. The object 40 of this adjustment is to secure and maintain the required power transmission between power shaft 34 and regulating shaft 32, with respect to the speed with which the clay bar is extruding, and also with respect to 45 the consistency or stiffness of the clay, so as to synchronize the actuation of the wire reel with the movement of the clay bar.

The devices for lubricating the clay bar serve to facilitate its passage over the platens both as to its underside and the rear face which support the bar as the cutting wires 50 pass through same.

What I claim is:—

1. A brick machine having a horizontally 55 movable housing, a wire reel rotatably mounted therein, and means for causing a periodic rotative movement of the wire reel, including a power shaft, a pinion, a coöperating gear on the wire reel, elements forming 60 a positive locking clutch operating between the power shaft and pinion, and automatic means for shifting a clutch element, comprising a rocking lever and a pair of rotating cams adapted alternately to coact 65 with the opposite ends of said lever, one

cam operating to cause the engagement of the clutch elements and the other cam operating to cause their disengagement.

2. A brick machine as defined in claim 1, in which means are provided whereby one 70 of the cams operates only while the clutch is effective between the power shaft and the pinion.

3. A brick machine having a horizontally 75 movable housing, a wire reel rotatably mounted therein and means for causing a periodic rotative movement of the reel including a power shaft, a pinion, a coöperating gear on the reel, a positive clutch operating between the power shaft and pinion and automatic means for shifting a clutch 80 element and driving the same synchronously with the movement of the clay bar, said positive clutch comprising a ratchet formation as one element and a 85 housing provided with a plurality of co-acting pawls as the other element.

4. A brick machine as defined in claim 3, in which the ratchet and pawls have co-operating beveled or inclined faces for 90 facilitating their co-action.

5. A brick machine having a horizontally 95 movable housing, a wire reel rotatably mounted therein and means for causing a periodic rotative movement of the reel including a power shaft, a pinion, a coöperating gear on the reel, a positive clutch operating between the power shaft and pinion and automatic means for shifting a clutch 100 element and driving the same synchronously with the movement of the clay bar, said driving means including an adjustable friction clutch for the transmission of power between the power shaft and the regulating shaft which is controlled by the clay bar. 105

6. A brick machine having a horizontally 110 movable housing, a wire reel rotatably mounted therein and means for causing a periodic movement of the reel including a power shaft, a pinion, a coöperating gear on the reel, a positive clutch operating between the power shaft and pinion, and automatic means for shifting a clutch element, comprising a rocking lever, a cam for actuating the same and an over-the-center spring 115 controlled mechanism for completing the cam-actuated movement of the lever.

7. A brick machine as defined in claim 6, in which the spring controlled mechanism serves to maintain the shift lever in 120 either extreme position of its movement, with the clutch elements engaged or disengaged.

8. A brick machine having a wire reel, and actuating mechanism therefor, including a positive clutch, and mechanism for causing the engagement and disengagement of the clutch elements comprising a cam, a cam operated rocking lever, a shift lever actuated thereby, a cam shaft and means 125 130

whereby the shaft is capable of a partial movement independently of the cam.

9. A brick machine as defined in claim 8 in which means are provided whereby the cam is capable of a spring actuated movement independently of the cam shaft.

10. A brick machine as defined in claim 8, in which the cam is provided with a sector shaped recess and the shaft with a projec-

tion operating in said recess to secure limited independent movement between cam and shaft.

11. A brick machine as defined in claim 10, in which a spring is secured between the shaft and the cam as means whereby the relative movement therebetween puts the spring under tension.

ARTHUR ROOT.
